TRUCK MOUNTED HOIST

Norman J. Farnam, Enumclaw, Wash.

Application June 22, 1954, Serial No. 438,442

1 Claim. (Cl. 212—53)

This invention relates generally to hoist mechanisms and has for its primary object the provision of a truck mounted hoist particularly useful for loading objects, such as logs, onto the beds of trucks.

Another object of this invention is to provide an improved truck mounted hoist and novel mounting means therefor which is readily adaptable for use on truck bodies and which includes a novel boom and mast construction incorporating a free swinging boom member and a mast selectively positionable in any one of several positions to effect the desired loading characteristics, together with sluing means for the boom.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is side elevational view of a truck equipped with the improved hoist mechanism;

Figure 2 is a plan view of the hoist assembly;

Figure 3 is a vertical irregular section taken substantially along the plane of section line 3—3 in Figure 1;

Figure 4 is a horizontal section taken substantially along the plane of section line 4—4 in Figure 1;

Figure 5 is a vertical section taken substantially along the plane of section line 5—5 in Figure 1;

Figure 6 is a vertical section taken substantially along the plane of section line 6—6 in Figure 4;

Figure 7 is a fragmentary vertical section taken through the mast assembly; and

Figure 8 is a horizontal section through the mast assembly slightly above its flanges showing a modified form of construction.

Referring now more particularly to the drawings, reference numeral 10 indicates an automotive truck which is provided with a conventional bed assembly 12, the truck having the usual longitudinal frame members 14 and 16. At the forward end of the bed 12 is mounted a standard or base 18 of generally A-shaped configuration which includes the downwardly divergent legs 20 and 22 rigidly secured at their lower ends to the frame rails 14 and 16, respectively. Adjacent the upper end of the legs 20 and 22 is a cylindrical member 24 which is provided at its upper free end with an annular flange member 26 rigidly secured thereto, as by welding or the like, and, as will be seen most clearly in Figure 7, member 24 is adapted to receive the lower end portion 28 of a mast 30, the mast being provided at an intermediate point with an annular flange or collar member 32 which rests upon the upper surface of the aforementioned flange 26 for rotatably mounting the mast within the cylindrical member 24. The flange 32 is provided with a plurality of circumferentially spaced openings through which a lock pin 34 is selectively received and the flange 26 is provided with a single opening in the position shown clearly in Figure 7 also receiving this pin, and it is to be noted that in this manner, the mast 30 may be ro-

2

tatably positioned with respect to the cylinder 24 in any one of the several positions corresponding to the various openings in the flange 32.

The flange 32 is provided with a pair of spaced bracket ears 36 between which are rigidly secured the bearing members 38 disposed in vertically spaced relation for reception therebetween of an arm portion 40 of the sheave support assembly 42. A vertical pivot pin 44 rotatably connects the sheave support assembly 42 to the bracket ears 36. A boom 46 is pivotally connected to the sheave support 42 by a horizontal pivot pin 48 and the free end of this boom carries a sheave 50 in the manner shown.

The upper end of the mast 30 is provided with a pair of spaced radial arm members 52 between which a sheave 54 is journaled, as by the pin 56, and to the free end of these bracket arms is connected a chain 58 which includes a detachable link 60 for shortening or lengthening the chain and a cable 62 connected to the free end of the chain is anchored to the sheave 50 at the end of the boom. Since chain 58 is of a fixed length, when boom 46 is swung laterally the chain 58 causes boom 46 to rise slightly and this provides a sluing force tending to restore the boom to its normal position over the truck body.

As seen most clearly in Figures 4—6, a pair of support straps 64 are secured transversely between the frame members 14 and 16 and midway thereon are mounted the bearing members 66 and 68 within which the longitudinally extending shaft 70 is journaled. Rigidly secured to the shaft 70 directly beneath the cylindrical mast 24 is a drum 72 upon which one end of a cable 74 is wound. One flange 76 of the drum is provided with a conical recess 78 defining a female clutch member 80 adapted to cooperate with the male clutch element 88 which is rigid with the shaft 70. The element 88 has a sprocket 82 over which a chain 84 is trained which, by engagement over a sprocket on the lay shaft 86 imparts drive force to the clutch element 80. In this respect, the lay shaft 86 is suitably connected to a power take-off transmission 89 of the vehicle.

The forward end of the male clutch element 80 provides a thrust surface against which the cam element 88 is engaged. The cam element 88 is connected by means of a link 90 to a hand control lever 92 such that upon outward movement of the lever 92, the element 88 will bear against the thrust end of the element 80 and urge this element into engagement with the female clutch element defined by the recess 78, in opposition to the spring 94 normally maintaining these elements out of engagement to effect a drive to the drum 72. The drum flange 76 also provides a brake surface on its outer face and a brake strap 96 dead-ended at one end to the vehicle frame extends around this flange for connection to a point on the brake control lever member 98 mounted on the vehicle through a horizontal pivot pin 100 such that upon manipulation of the lever 98, the brake strap will tighten and hold the drum in a desired position.

The cable 74 issues from the drum 72 and passes upwardly therefrom through the cylindrical member 24 and the mast 30 and over the sheave 54 previously described, and thence downwardly over the sheave assembly 42 and outwardly therefrom to the free end of the boom over the sheave assembly 50 and is provided at its free end with a grapple such as the log tongs 102. In operation, the mast 30 is secured in a selected rotatable position with respect to the cylindrical member 24 by insertion of the locking pin 34 in a desired one of its openings and the boom 46 is manually swung, for example, pulling on the free end of the cable 74, such that the boom swings to one side of the truck or the other for picking up a load, such as a log. The drum clutch is

engaged to lift the load, and the weight of the load will tend to swing the boom 46 to a position coincidental in direction with the direction in which the bracket arms 52 extend due to the fact that the chain 58 is connected to the free end of the bracket arms 52 at a point radially outwardly from the mast 30 with respect to the position which the vertical pivot pin 44 occupies. This will effect a sluing moment arm about the pivot pin and swing the boom 46 to the aforementioned coincidental position with the bracket arms 52. Thus, if it is desired to load a log directly on the truck bed 12, the bracket arms 52 are positioned as shown in Figure 1, and the boom 46 will automatically displace to the position shown in this figure when the log has cleared the side of the truck bed.

As an aid to manipulating the boom when the truck may be disposed on uneven surfaces or whenever the truck is disposed out of level, it may be desired to provide hydraulic cylinder members 104 for controlling the movement of the flange 32 and consequently the rotatable position of the mast 30. In this respect, it will be seen that one end of each of the cylinders 104 is connected to the opposite ends of a cross-brace member 106 rigid with the A-frame assembly 18 with the free end of the piston rod 108 connected to the flange 32. The cylinders may, of course, be controlled by any suitable valve mechanism for effecting the rotatable positioning of the mast 30. In other respects the construction of the modification in Figure 8 is the same as the previously described form of the invention.

It will be readily appreciated that the A-frame assembly not only provides a very rigid mounting for the hoist, but also permits the drum assembly 72 to be advantageously positioned directly beneath the cylindrical member 24 such that the cable 74 passes upwardly therethrough and through the mast 30. This is an added safety feature in the event that the cable 74 snaps, since there is less chance for whipping of the cable in the event of such snapping. The bracket arms 52 may be positioned in any one of a plurality of rotatable positions with respect to the cylindrical member 24 such that a load may be placed at will. For example, when it is desired to unload the truck bed and place the objects to one side of the truck, the bracket arms 52 will be positioned transversely to one side of the truck or the other which will effect positioning of the boom 46 in a corresponding manner when the load is freely supported by the boom.

From the foregoing, the construction and operation of the device will be readily understood and further ex-

planation is believed to be unnecessary. However, since numerous modifications and changes will readily occur to those skilled in the art, it is not desired to limit the invention to the exact construction shown and described, and accordingly, all suitable modifications and equivalents may be resorted to, falling within the scope of the appended claim.

What is claimed as new is as follows:

In combination, a load receiving bed, a hoist support rising from and secured to said bed and including an upper cylinder provided with a circumferential flange, a hollow mast having a cylindrical lower end portion rotatably disposed in said cylinder and an upper portion rising out of said cylinder, a circumferential flange fixed to said mast and forming the separation between said portions, said circumferential flange being rotatable on said first named flange, a vertical pivot pin on the second named flange, a sheave support pivoted on said pin for lateral swinging and provided with a first sheave outwardly of said pin, a boom secured to said sheave support for lateral swinging, a radial arm on said mast above said sheave support, a second sheave on said mast above said first sheave, a third sheave on the outer end of said boom, a load lifting cable, drum means for winding up said cable to lift a load, said cable extending upwardly through said hollow mast and over the second sheave, thence downwardly under the first sheave and from the first sheave over the third sheave and a flexible elongated sluing means secured to said radial arm and the outer end of said boom so that under load on said cable said sluing means cooperates with said cable and will tend to swing said boom laterally about said pin into vertical alignment with said arm.
